UNITED STATES PATENT OFFICE

SOLOMON PITKIN, OF NEW YORK, N. Y.

FINGER AND BACK STRAP FOR HAND BAGS

Application filed July 26, 1928. Serial No. 295,439.

This invention relates generally to ladies' hand bags and pocket books, and has more particular reference to a novel combination finger and back strap therefor.

5 The invention has for an object the provision of a device of the class mentioned, which is of simple durable construction, desirable and efficient in action, and which can be manufactured and sold at a reasonable 10 cost.

The invention proposes the use of a strap attached at its bottom end on the rear side of a hand bag in proximity of the bottom, and extending upwards past the top of the hand 15 bag and then looped around for forming a finger grip opening, and finally having its top end attached on the side of the bag at a point whose distance from the top of the bag is slightly more than the diameter of an average person's index finger. A loop member extends over the strap at this point, and is attached onto the hand bag. The said strap should vary in width so that the portion between the bottom end of the loop member may 20 be drawn rearwards for forming a back strap at the expense of the finger grip. That is the finger grip is reduced in size to just about accommodate one's finger, and in this condition it cannot be seen from the front side 25 of the hand bag. A lug member may be adjustably mounted on the hand bag and arranged for varying the passage of the said loop member for limiting the passage of the strap thru the loop member and thus determining the final reduced size of the finger 30 grip.

For further comprehension of the invention, and of the object and advantages thereof, reference will be had to the following description and accompanying drawings, and to the appended claims in which the various novel features of the invention are more particularly set forth.

35 In the accompanying drawing, forming a material part of this disclosure:

Fig. 1 is a rear side elevational view of a hand bag provided with the device.

Fig. 2 is an end view thereof.

Fig. 3 is another end view, but illustrating 40 the strap in a position in which the back

strap is operative and the finger grip is reduced:

Fig. 4 is a rear side elevational view thereof.

Fig. 5 is an end view similar to Fig. 3, but illustrating a modified form of the device. 55

Fig. 6 is a fragmentary horizontal sectional view, taken on the line 6-6 of Fig. 5.

Fig. 7 is a view similar to Fig. 6 but illustrating a modification of the device.

The reference numeral 10 indicates generally a hand bag of any design or construction having a top edge 11, a bottom edge 12, a front side 13 and a rear side 14. A strap 15, preferably of leather, is attached at its bottom end on the rear side 14 of the hand bag 15 in proximity of the bottom 12, as indicated by numeral 16, and extends upwards past the top 11 of the hand bag, and then is looped as at 17 for forming a finger grip loop opening 18, and finally has its top end secured as indicated by numeral 19 on the rear side 14 of the hand bag at a point whose distance from the top 11 is slightly more than the diameter of an average person's index finger. A horizontal loop member 20 is attached at its ends on the rear side 14 of the hand bag, and extends over the strap 15 at substantially the point 19. 70

The lower portion of the strap 15 has parallel sides joining an intermediate reduced portion 21 which passes thru the loop member 20, and which further on expands into an enlarged portion 22 arranged for striking the ends of the loop member and restrains a complete passing of the strap thru 75 the loop member.

In operation of the device a person may pass one or more fingers thru the opening 18 for carrying the hand bag in a depending condition. When desired the strap 15 may be 80 pulled thru the loop member 20 until limited by the enlarged portion 22 as shown in Figs. 3 and 4 for forming a back strap opening 23 and a small loop opening 24 for engagement 85 for pulling the strap back into original position.

The fingers of a person may then be passed thru the opening 23 so that the palm rests against the rear side 14 of the bag for carrying the hand bag firmly. It is pointed out that 100

the strap 15 as shown in Fig. 3 is not visible from the front side of the hand bag for reason of the position of the loop member 20.

The modified form of the device illustrated in Figs. 5 and 6 discloses the top end of the strap 15 attached to the loop member 20 as at 19^a, otherwise the shape of the strap and the operation of the device is the same as given in the preferred form.

10 In Fig. 7, a lug member 25 is shown extending within the loop member 20, and having a rear extension 26 with a slot 27 engaged by a stud 28 fixed on the bag 10 and provided with a wing set nut 29 for locking the lug member into fixed positions so as to vary the width of the loop member and change the points on the strap 15 which engage the loop member for limiting the amount of strap passable thru the loop member and thus permit adjustment of the size 15 of the opening 24 or 23 for accommodating person's fingers of different sizes.

While I have shown and described the preferred embodiment of my invention, it is 25 to be understood that I do not limit myself to the precise construction herein disclosed and the right is reserved to all changes and modifications coming within the scope of the invention as defined in the appended claims.

20 Having thus described my invention what I claim as new and desire to secure by United States Letters Patent is:

1. In a device of the class described, a combination finger and back strap arranged in 25 one position for providing a finger loop for carrying the device in depending condition and in another position for providing a loop for carrying the device with fingers engaged in this loop and one's palm pressed against the device.

2. In a device of the class described, a strap attached at its bottom end on the device, and extending upwards past the top of the device, and looped around for forming a finger grip opening, and having its top end attached on the device at a point whose distance from the top of the device is more than the diameter of an average person's index finger, and a loop member 45 attached on the device, and extending over the strap at the region of attachment of the top end of the strap for permitting the lower portion of the strap to be drawn outwards so as to form a back strap opening for the device.

3. In a device of the class described, a strap attached at its bottom end on the device, and extending upwards past the top of the device, and looped around for forming a finger grip opening, and having its top end attached on the device near the top thereof, and a loop member attached on the device, and extending over the strap at the region of attachment of the top end of the 60 strap for permitting the lower portion of

the strap to be drawn outwards so as to form a back strap opening for the device.

4. In a device of the class described, a strap attached at its bottom end of the device, and extending upwards past the top of the 70 device, and looped around for forming a finger grip opening, and having its top end attached on the device near the top thereof, and a loop member attached on the device, and extending over the strap at the 75 region of attachment of the top end of the strap for permitting the lower portion of the strap to be drawn outwards so as to form a back strap opening for the device, the top portion of the strap being of enlarged 80 width for restraining complete drawing of the strap thru the loop member.

5. In a device of the class described, a strap attached at its bottom end of the device, and extending upwards past the top 85 of the device, and looped around for forming a finger grip opening, and having its top end attached on the device near the top thereof, and a loop member attached on the device, and extending over the strap at the 90 region of attachment of the top end of the strap for permitting the lower portion of the strap to be drawn outwards so as to form a back strap opening for the device, the top portion of the strap being of enlarged 95 width for restraining complete drawing of the strap thru the loop member and arranged for forming a finger loop disposed beneath the top edge of the device.

6. In a device of the class described, a 100 strap attachment at its bottom end of the device, and extending upwards past the top of the device, and looped around for forming a finger grip opening, and having its top end attached on the device near the top thereof, and a loop member attached on the device, and extending over the strap at the 105 region of attachment of the top end of the strap for permitting the lower portion of the strap to be drawn outwards so as to form a back strap opening for the device, the top portion of the strap being of enlarged width for restraining complete drawing 110 of the strap thru the loop member and arranged for forming a finger loop disposed beneath the top edge of the device, a lug being adjustably mounted on the device and extending into the loop member for varying the width thereof for the purpose stated.

In testimony whereof I have affixed my 120 signature.

SOLOMON PITKIN.
